UNITED STATES PATENT OFFICE

FRANK L. JOHNSON, OF STATESVILLE, NORTH CAROLINA

DESIGN FOR A BOTTLE

Application filed September 28, 1929. Serial No. 32,893. Term of patent 7 years.

To all whom it may concern:

Be it known that I, FRANK L. JOHNSON, a citizen of the United States, residing at 908 Davie Ave., city of Statesville, in the county of Iredell and State of North Carolina, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.
